E. R. HILDEBRANDT

ADJUSTABLE CORE BOX

Filed March 16, 1921

Inventor:

Ernest R. Hildebrandt.

By Howard J. Hildebrandt

his Attorney.

UNITED STATES PATENT OFFICE.

ERNEST R. HILDEBRANDT, OF ST. PAUL, MINNESOTA.

ADJUSTABLE CORE BOX.

Application filed March 16, 1921. Serial No. 452,707.

To all whom it may concern:

Be it known that I, ERNEST R. HILDEBRANDT, a citizen of the United States, residing at St. Paul, in the county of Ramsey and State of Minnesota, have invented a new and useful Improvement in Adjustable Core Boxes, of which the following is a specification.

My invention relates to piston mold making devices and has for its object to provide a piston mold making device in which the length of the piston and the relative positioning of the piston bosses and ring grooves may be varied at will.

15 In carrying out my invention I employ a core box and pattern formed with a body portion and a sleeve of relatively thin material adapted to slide along said body portion with means for adjustably holding the same in fixed relation to said body portion. On the core box I provide means for adjustably holding the bosses in any adjusted position.

20 The full objects and advantages of my invention will appear in connection with the detailed description thereof and are particularly pointed out in the claims.

25 In the drawings, illustrating the application of my invention in one form:—

30 Fig. 1 is a cross sectional view of a portion of a mold box showing the piston mold formed therein by means of my invention.

Fig. 2 is an elevational view of the pattern.

35 Fig. 3 is a cross sectional view of the pattern shown in Figure 2.

Fig. 4 is a plan view of the core box.

Fig. 5 is a vertical sectional view of the core box.

40 Fig. 6 is an end view of the pattern shown in Figure 3.

In Figure 1, I show the mold of a typical form of piston such as I desire to mold with my improved piston molding device. This 45 mold comprises an inner cavity 10 formed in the shape of the exterior of the piston and a core 11 having a core print 12 adapted to fit into a corresponding depression 13 in the mold proper, by means of which said

50 core 11 is suspended into the cavity 10 as clearly indicated in Figure 1. The piston as indicated by the mold in Figure 1 is required to have an enlarged portion 112 immediately adjoining its head 113 and to be 55 provided with bosses 15 and two rings 17

positioned around the periphery of the same near its lower end. In casting pistons it is desirable to be able to cast a piston and the enlarged portion 112 of any desired length and to be able to position the bosses 60 within said piston at any desired locality. In my invention I perform these objects by constructing the parts comprising the pattern and core box of the piston adjustable so that the length of the piston and portion 65 112 and the positions of the boss may be varied at will without adding additional parts to the device so that each of these members is a complete unit in itself.

The pattern for the piston which is clearly 70 shown in Figs. 2 and 3 comprises a cylindrical head 18 which is preferably cast, and is turned with a cylindrical surface 19 and a square face 20 at the end thereof. Upon the exterior of surface 19 is adapted to slide 75 a sleeve 21 formed of relatively thin sheet iron which is secured to a core print 22 as follows. The extreme end 23 of sleeve 21 is adapted to project into a socket 24 formed in the lower portion of core print 22 as best 80 indicated in Figure 3. Sleeve 21 is adapted to snugly fit this socket and is held in place by means of an annular ring 26 adapted to lie adjacent the inner surface of the end 85 23 of said sleeve. The ring 26 is split transversely at 27 and is formed with a conical hole. A screw 28 is adapted to pass through the ring 26 at its point of severance 27 and through a wall 30, a core box and is provided with a nut 31 positioned on the opposite side of wall 30 so that as the screw is 90 rotated and head 29 drawn towards wall 30 the ends of said ring 26 are spread apart causing the periphery of said ring to engage the portion 23 of sleeve 21 and to force 95 said sleeve against the socketed cavity 24 in the end of core print 22. In this manner sleeve 21 is clamped within core print 22 so as to prevent removal of the same excepting by unloosening ring 26.

100 Head 18, which as before stated, is slidably mounted within sleeve 21, is adapted to be advanced along said sleeve by means of a threaded rod 32 which can be screwed into a threaded neck 33 formed along the 105 axis of the piston and attached to the end 20 thereof. The threaded rod 32 is formed with a shoulder 34 and a threaded portion 35 which is adapted to pass through a boss 36 formed at the center of core print 22 and 110

to be attached to said core print by means of a nut 37 screwed upon the protruding end of rod 32. The rod 32 is adapted to be screwed into the threaded neck 33 which is threaded throughout the entire length and is provided with a plug 34 formed in the end thereof for the purpose of keeping sand from entering the pattern when the same is in use and which also serves for forming 10 a boss in the mold to be cast on the piston. A cover plate 38 is secured to the core print 22 by means of screws 39 and is adapted to conceal the nut 37 and the nut 31 by means of which the various parts are held together 15 and to present a smooth surface to the exterior of the pattern. In manipulating the device the sleeve 21 and the core print 22 are held in one hand and head 18 rotated relative thereto, the neck 33 being screwed 20 upon the threaded rod 32 causing the end 20 of head 18 to advance or retreat as said head is rotated. In this manner the length of the pattern may be varied at will to give any length of piston without removing any 25 portion of the device or by inserting additional sections to the same.

After the head 18 has been rotated to make the pattern of the desired length the same may be locked in place by means of 30 a device shown in Figures 3 and 6. The end of the rod 32 is split for a portion of its length at 40 and is also internally threaded at 41 for a length to correspond with the slot 40. A tapered threaded plug 42 is 35 adapted to screw into the threaded portion 41 so as to cause the ends of rod 32 to spread as said plug is screwed into the rod. This causes the ends of rod 32 to bind against the inner walls of neck 33 thereby firmly holding 40 the head 18 positioned on rod 32 within sleeve 21. In order to manipulate this locking device it is merely necessary to remove the plug 34 and insert a screw driver through the neck 33 to engage the plug 42. 45 After the head has been properly positioned in the locking device said plug 34 may again be replaced making the device ready for use.

In conjunction with the pattern above described I employ a core box having similar adjustable features which is shown in detail in Figures 4 and 5. The core box is made with a body portion 43 which is made to conform to the surface of the interior of the piston and is so constructed that only a 50 half of the core is made at one time. This body portion is provided with legs 44 and 45 so that the core box may stand on a table to permit the operator to readily fill the same with the core sand. Body 43 as is 55 shown is semi-cylindrical throughout its length excepting at 46 where the same is formed with an enlarged head adapted to form the core print 12 when the core is formed. A cover plate 47 is fastened onto 60 head 46 by means of screws 48 which serves

to form the end of said core print. Within the cylindrical body portion 43 is slidably mounted a partition 49 which is adjustably positioned on a semi-cylindrical sleeve portion 50. By properly positioning said partition on the sleeve portion 50 a protrusion within the same at one end may be provided as indicated at 51, which forms the enlarged portion 12 of the piston proper. Partitions 49 and member 50 are adapted to be clamped 70 to body member 43 by means of a machine screw 52 having a counter sunk head which passes through said partition member 49, through a longitudinal slot 53 formed substantially along the entire bottom of body member 43, and another longitudinal slot 200 formed along the bottom of member 50. A nut 54 screwed upon the end of screw 53 serves to clamp partition 49 and sleeve 50 in any position relative to each other upon the semi-cylindrical body member 43 in any position along the same. In this manner the length of the core may be properly adjusted in relation to the length of the pattern so that the right thickness of the piston head 113 may be secured and the length of the enlarged portion 112 varied as required.

For forming the bosses in the cylinder I provide a boss 55 which has a machine screw 56 passing through it which is adapted to protrude through the slot 53 and may be secured in any position along said slot by means of a nut 57 similar to the method of securing the partition 49. By sliding boss 55 along slot 53 the position of this boss relative to the head of the cylinder can be varied at will. To cover up the slot 53 between the boss 55 and sleeve member 51 and between said boss and the core print of this device I provide two strips of sheet iron 58 and 59 which are adapted to be inserted between the body member 43 and the boss 55 in sleeve 51 so as to be firmly clamped in place as these members are secured in position upon the body portion 43. As the core is filled leakage of the same through slot 53 is hence prevented by these two devices. In molding pistons I find it advisable to make the core in two halves and to paste these two halves together. For this purpose I have shown my core box as comprising one half only, though it can be readily understood that if it were desired to make the core box in two pieces another half could be added to the box similar to this one and the two secured or clamped together.

In using my invention the pattern is first 125 adjusted to the proper length and a mold made of it in a mold box of ordinary construction not shown in the drawings, with the parting line of the mold at 60 as indicated in Figure 1. As the sleeve 21 is positioned outside of head 18 it can be easily 130

seen that the pattern can readily be withdrawn from the mold, as the diameter of the head 18 must be less than the sleeve 21 by a difference equal to the thickness of the metal in the sleeve. A core is prepared in the usual manner in two halves which are pasted together to form a complete core which is inserted into the mold indicated at 10 in Figure 1 in a position so that the core print formed on said core fits into the corresponding depression 13 in the mold formed for that purpose. This leaves the core properly spaced from the exterior wall of the mold so as to give the piston the desired form and thickness.

The advantages of my invention are manifest. A single core box and pattern are required for any diameter of piston which may be adjusted to any length of piston with any location of boss within the same without dismounting the entire structure and without the removal or addition of additional parts. In the ordinary form of adjustable core box in which a number of sections are used it becomes necessary to have a great number of parts due to the number of combinations necessary to handle all lengths of pistons varying by small fractions of an inch. With such devices the cost becomes prohibitive. With my invention I require but one pattern for each diameter of piston. If desired the length of piston or the positioning of the bosses within the same may be varied by any amount desired.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. A piston molding device comprising a socketed cover member, a sleeve positioned within said socketed member, a head slidably mounted within said sleeve, an operating member for sliding said head passing through said cover member, means attachable upon the end of said operating member for securing the same to said cover member, a flange formed on said cover member, and a plate positioned on said flange for concealing said securing means.

2. A piston molding device comprising an outer sleeve, an inner sleeve slidable within said outer sleeve, an end block slidable within said inner sleeve, and means for simultaneously locking both of said sleeves and said end block in any of their adjusted positions.

3. A piston molding device comprising a sleeve, a head slidably mounted within said

sleeve for varying the length of the piston, and means for holding said head in locking position within the sleeve.

4. A piston molding device comprising a sleeve, a head slidably mounted within said sleeve for varying the length of the piston, means for holding said head in locking position within the sleeve, and a cover member adapted to be secured to said sleeve for closing the end thereof.

5. A piston molding device comprising a sleeve, a cover member secured to said sleeve at one end thereof, a head adapted to slide within said sleeve, a screw secured to said cover and a threaded portion formed on said head adapted to be screwed along said screw as the head is rotated within said sleeve, and means for locking the end of said screw within the threaded portion of said head.

6. A piston molding device comprising a sleeve, a cover member for said sleeve having a socketed depression within the same, said sleeve being adapted to fit into said socketed depression, a split annular member adapted to be positioned within said sleeve, and means for spreading said split annular member apart to clamp the sleeve against the walls of said socketed cover member.

7. A piston molding device comprising a sleeve, a cover member for said sleeve having a socketed depression within the same, said sleeve being adapted to fit into said socketed depression and means for clamping said sleeve against the walls of said socketed cover member.

8. A piston molding device comprising a sleeve, a cover member secured to said sleeve at one end thereof, a head adapted to slide within said sleeve, a screw secured to said cover and a threaded portion formed on said head adapted to be screwed along said screw as the head is rotated within said sleeve, and means for spreading apart the end of said screws to cause the same to bind within the threaded portion of said head.

9. A piston molding device comprising a sleeve, a longitudinal slot formed along said sleeve, a head slidably mounted within said sleeve, means for guiding and locking said head in any position along said slot.

10. A piston molding device comprising an outer sleeve, a longitudinal slot extending through said sleeve, an inner sleeve, a longitudinal slot extending through said inner sleeve for a portion of the length thereof, and registering with said outer sleeve slot, an end block slidably mounted within said inner sleeve and a bolt passing through said end block and through both of said sleeve slots for clamping said sleeves and end block together in any of their adjusted positions.

11. A piston molding device comprising an outer sleeve, a longitudinal slot extend-

ing through said sleeve, an inner sleeve, a longitudinal slot extending through said inner sleeve for a portion of the length thereof, and registering with said outer sleeve slot, an end block slidably mounted within said inner sleeve and a bolt passing through said end block and through both of said sleeve slots for clamping said sleeves and end blocks together in any of their adjusted positions, and a cover member for closing the portion of said slot positioned within said mold.

12. A piston molding device comprising a sleeve, a slot formed in said sleeve and passing through the same, a member slidable

within the sleeve and secured to the same through said slot, and a cover member adapted to close the portion of said slot positioned within the mold.

13. A piston molding device comprising a sleeve, a slot formed in said sleeve and passing through the same, a member slidable within the sleeve and secured to the same through said slot, and a cover member adapted to close the portion of said slot positioned within the mold, said cover member being adapted to be clamped between said sleeve and said slid able member.

ERNEST R. HILDEBRANDT.
